LID FASTENER

John B. Smith, Jr., Vicksburg, Miss., assignor of
one-half to Henry Q. Brackett, Vicksburg,
Miss.

Application September 23, 1940, Serial No. 357,963

1 Claim. (Cl. 220—61)

This invention appertains to new and useful improvements in lid fasteners for receptacles of various kinds.

The principal object of the present invention is to provide a lid fastener which can be readily fastened or unfastened to permit snug application or removal of the corresponding lid.

Other objects and advantages of the invention will become apparent to the reader of the following specification.

In the drawing:

Figure 1 represents a vertical sectional view through a can and lid with the fastening means applied.

Figure 2 is a sectional view taken substantially on the line 2—2 of Figure 1.

Figure 3 is a side elevational view of a can and lid, with the fastening means applied.

Figure 4 is a side elevational view of the special lid.

Referring to the drawing wherein like numerals designate like parts, it can be seen that numeral 5 denotes a can having a special type lid 6. This lid 6 consists of a top *a* and a depending skirt *b* oversize with respect to the can 5. The top *a* has a handle 7.

Numeral 8 generally refers to the fastening means which consists of an elongated spring strap 9 having its intermediate portion riveted or otherwise secured at 10 to the inner side of the skirt *b*. At a diametrically opposite point from the rivet 10, the skirt *b* is formed with a pair of substantially rectangular shaped openings 11—12, portions being bent inwardly to define guides 13 and 14 for the end portions of the strap 9.

The fastener consists further in the provision of a rectangular-shaped link 15. One end of the strap 9 has a barrel 16 which receives one end of the link 15. The other end of the strap 9 has a hook 17. An elongated lever 18 being substantially arcuate to follow the curvature of the skirt *b* and having an offset end portion 19, has one end formed to provide a barrel 20 receiving the remaining end of the link 15 and on which end

portion of the link, the lever is fulcrumed. From this barrel 20 extends a foot portion 21 which is engageable in the hook 17 of the strap 9. When the lever 18 is released, the hook 17 will engage one edge of the opening 11 and the strap 9 will be slackened sufficient to permit ready removal of the lid 6 from the can 5.

To secure the lid in place, the foot 21 is engaged with the hook 17 and the lever 18 swung so that the link 15 is carried over the hook 17 and the lever 18 brought to bear against the side of the skirt 6.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In combination with a receptacle, a lid having a skirt fitting over the open end of the receptacle, an elongated spring strap having an intermediate portion secured to the inside of the skirt and said skirt having a pair of spaced openings therein arranged substantially opposite the point of fastening of the strap to the skirt, an open-work link having one end pivotally connected to one end of the strap and said end of the strap passing through one opening, a hook on the other end of the strap passing through the other opening with said hook engaging an edge wall of said other opening when the strap is expanded, a lever pivoted intermediate its ends to the opposite end of the link with the inner end of the lever being straight for engaging the hook of the strap and the other portion of the lever forming a handle, said lever being of arcuate shape to conform to the curvature of the skirt when in holding position with the straight inner end engaging the hook of the strap and contracting the strap about the receptacle.

JOHN B. SMITH, JR.
